UNITED STATES PATENT OFFICE

WALTER AIKEN, OF FRANKLIN, NEW HAMPSHIRE.

IMPROVEMENT IN KNITTING-MACHINES.

Specification forming part of Letters Patent No. 43,170, dated June 21, 1864.

To all whom it may concern:

Be it known that I, WALTER AIKEN, a resident of Franklin, in the county of Merrimac and State of New Hampshire, have invented a new and useful Improvement in Machines for Knitting; and I do hereby declare the same to be fully described in the following specification and represented in the accompanying drawings, of which—

Figure 1 is a vertical section of a knitting-machine needle-plate, as provided with my invention. Fig. 2 is a top view of a portion of such needle-plate. Fig. 3 represents the needle-plate in section, and as provided with a needle of the kind which is applicable to it.

In the drawings, A denotes the needle-plate, which is a circular annulus provided with radial grooves made in its upper surface, in each of which a needle is to be placed and held so as to be capable of being moved endwise or longitudinally, as circumstances may require, the upper surface of the shank of the needle being flush, or about so, with the upper surface of the plate.

The needle to operate in the plate as furnished with my improvement is one provided with two projections extending in opposite directions from its shank, the upper of the said projections entering a cam-groove of a rotary plate. The lower of the projections is for steadyng the needle or preventing it from

turning within its groove while the needle may be in use. In order that the said lower projection may operate to the requisite advantage, the needle-groove *a* of the needle-plate is constructed with a depression, *a'*, extending below the bottom of the groove or that part *b* of it on which the shank of the needle rests. Generally speaking, the depth of the depression *a'* should correspond with the distance to which the lower projection of the needle extends beyond the shank.

As the needle has to play loosely in its guiding groove, it is liable, especially should the groove become worn a little wider than the needle, to turn in its groove. To prevent this is the office of the depression *a'*, acting in conjunction with the lower projection of the needle, such depression being of a length sufficient to allow of the necessary movements of the needle.

I claim—

The needle-plate as made with the depression *a'*, arranged below its needle-groove *a*, and to operate with a needle when made with a projection to extend downward from its shank, as set forth.

WALTER AIKEN.
